CLAIM

The ornamental design for an automobile interior, as shown and described.

DESCRIPTION

FIG. 1 is a left side perspective view of an automobile interior showing our new design;

FIG. 2 is a right side perspective view thereof;

FIG. 3 is a left side view thereof;

FIG. 4 is a right side view thereof;

FIG. 5 is a top view thereof; and,

FIG. 6 is a front view thereof.

The broken lines illustrate portions of the automobile interior which form no part of the claimed design.
